Des. 202,965
Patented Nov. 16, 1965

202,965

ASH TRAY

Howard R. MacDonald, 310 N. Ardmore Ave.,
Los Angeles, Calif.

Filed Apr. 5, 1965, Ser. No. 84,615

Term of patent 14 years

(Cl. D85—2)

FIG. 1 is a side elevational view of an ash tray showing my new design;

FIG. 2 is a top plan view;

FIG. 3 is a bottom plan view;

FIG. 4 is a sectional view on line 4—4 of FIG. 2; and

FIG. 5 is an exploded perspective view.

I claim:

The ornamental design for an ash tray, as shown.
